[57] CLAIM

The ornamental design for a case for baby teeth, as
shown and described.

DESCRIPTION

FIG. 1 is a perspective view of a case for baby teeth
showing my new design;

FIG. 2 is a top plan view thereof, the bottom plan view
being identical thereto;

FIG. 3 is a rear elevational view thereof;

FIG. 4 is a front elevational view thereof;

FIG. 5 is a left side elevational view thereof;

FIG. 6 is a perspective view thereof in the open position
with the transparent sliding inner cover partially open;
and

FIG. 7 is a top plan view of the open case.

FIG. 1.

FIG. 2.

FIG. 3.

FIG. 4.

FIG. 5.

FIG. 6.

FIG. 7.
